ATTORNEY.

UNITED STATES PATENT OFFICE.

ERNEST M. WHITE, OF LOS ANGELES, CALIFORNIA.

HOMOGENIZER.

1,423,170.

Specification of Letters Patent. Patented July 18, 1922.

Application filed July 8, 1918, Serial No. 243,917. Renewed July 1, 1921. Serial No. 482,003.

To all whom it may concern:

Be it known that I, ERNEST MILTON WHITE, a citizen of the United States, residing at Los Angeles, in the county of Los Angeles and State of California, have invented new and useful Improvements in Homogenizers, of which the following is a specification.

My object is to make a homogenizer for 10 furnishing explosive mixture from comparatively heavy oil for internal combustion engines, and my invention consists of the novel features herein shown, described and claimed.

15 Figure 1 is a fragmentary front elevation showing a heated intake manifold, and a carburetor connected to the intake manifold to produce a homogenizer in accordance with the principles of my invention, 20 parts being broken away and shown in section.

Fig. 2 is a vertical cross-section on the line 2—2 of Fig. 1 and looking in the direction indicated by the arrow.

25 Fig. 3 is a horizontal sectional detail on the lines 3—3 of Figs. 1 and 2.

Fig. 4 is a fragmentary vertical sectional detail showing a modified construction.

The intake manifold 1 consists of the 30 arms 2 and 3 leading outwardly and upwardly from the homogenizing chamber 4. A heating jacket 5 is formed integral with the intake manifold 1 and forms a chamber 6 around the wall of the homogenizing 35 chamber 4 and around the intake manifold arms 2 and 3. The fuel mixture passages 7 and 8 lead from the chamber 4 through the arms 2 and 3 to the cylinders of the engine when the manifold is connected to 40 an engine. An opening 9 leads to the top of the chamber 6 and openings 10 and 11 lead from the bottom of the chamber, the object being to connect the exhaust of the engine or the cooling water of the engine 45 jacket to circulate through the chamber 6 to heat the intake manifold. If water is used the connections will be made to run the hot water from the top of the engine jacket through the chamber 6 and then backwardly into the water jacket or radiator or the pipes connecting the water jacket to the radiator.

50 The chamber 4 is preferably circular in plan. A vertical bore 12 is formed through the head 13 at the bottom of the chamber 4 and at the vertical axial center of the

chamber. The lower face 14 of the head 13 is finished flat on a plane crosswise of the axis of the bore 12. The side wall 15 of the chamber 4 may be straight and parallel 60 with the axis of the bore 12 and the vertical axis of the chamber 4, said straight wall 15 forming nearly one-half of the height of the chamber. The upper portion of the chamber is formed by a wall 16 in the shape 65 of an annular semi-circular arch extending around the center point 17, said point 17 being in vertical alinement with the center of the bore 12. The lower portion of the chamber 4 is formed by a wall 18 drawn 70 upon the same lines as the wall 16 except that the bore 12 cuts away the central portion. The walls 15, 16 and 18 are formed integral and the openings 7 and 8 leading through the arms 2 and 3 lead through the 75 walls 15 and 18 may be on diametrically opposite sides and through the heating chamber 6.

A sleeve 19 fits tightly in the bore 12 and has a flange 20 fitting the flat face 14. The 80 upper portion of the sleeve 19 is reduced in size to receive the base 21 of the mixing tube 22 and which may be made with diverging walls above the openings 23 and 28. The base 21 of the mixing tube is somewhat 85 larger in diameter than the tube 22 and a series of radial openings 23 are formed through the tube 22 at the top of the base 21, the edges at the upper sides of the openings may be turned outwardly to form deflectors 24. The bore 25 through the sleeve 19 is tapered, preferably, to make a jet forming nozzle and with the mixing tube 22 forms an injector, and the upper edge 26 of the sleeve 19 may be beveled or inclined 90 from the inner face 27 of the wall 18 upwardly and inwardly so as to make a slight annular trough 28 around the upper end of the opening 25. The extreme upper end of the mixing tube 22 is preferably slightly below the point 17. A piece of twisted sheet metal is cut to fit in the mixing tube 22 to form a helix 29.

The carburetor 30 has a fuel mixture pipe 31 and a flange 32 at the upper end of the pipe 31, and cap screws 33 are inserted upwardly through the flange 32, through the flange 20, and tapped into the head 13. The throttle valve 34 is mounted in the pipe 31, the venturi 35 is mounted in the lower end 105 of the pipe 31, and the carburetor nozzle 36 is centrally located in the lower end of the 110

venturi 35, so that the nozzle will discharge straight up towards the point 17.

When the throttle 34 is opened more or less and the engine operating, the fuel mixture, 5 consisting of heavy gasoline, distillate, kerosene, or the like, passing upwardly through the nozzle 36 and mixing with air coming in around the nozzle through the venturi 35 will pass upwardly through the tapered jet 10 forming nozzle 25, around the helix 29, upwardly through the mixing tube 22 and strike the point 17 and this point will deflect the fuel mixture in all directions until it strikes the extreme top of the chamber 4, 15 and the walls 16, 15 and 18 being hot will vaporize a large portion of the solid particles of oil and the vapor will pass outwardly through the passages 7 and 8 fully vaporized fuel, and the particles of oil which fail to 20 vaporize the first time around will be thrown downward and sucked in through passages 23 by the suction caused by the injector action of the jet forming nozzle 25 and the mixing tube 22 and mixed with the mixture 25 discharged through the jet forming nozzle 25 and circulated again and again until the particles of fuel thrown downward are vaporized.

The homogenizing chamber 4 with the 30 vertical central jet forming inlet 25 forms a vortex having a central intake and a peripheral outlet and return passages.

If desired the helix 29 may be omitted.

In the modification shown in Fig. 4 the 35 fuel mixture passage 37 leads through the pipe 38 from the carburetor to the passage 39, preferably tapered to form a jet of high velocity to the gaseous fuel passing therethrough, and this passage or jet forming 40 nozzle 39 discharges into the mixing tube 40 and forming with it an injector, and the mixing tube 40 discharges the fuel mixture into the vortex chamber 45 from which the thoroughly vaporized mixture passes upward to the intake manifold through the passage 41. The vortex chamber 45 shown of irregular 45 shape in elevation has in it a core 42 forming one wall of the mixing tube 40, and one wall of the passage 43 adjacent the discharge end 50 of the jet forming nozzle 39. Toward the passage 43 the unvaporized particles of fuel are thrown substantially downward as they emerge from the mixing tube 40 and with a portion of the vaporized fuel are sucked 55 through the passage 43 and mixed with the gaseous fuel discharged from the jet forming nozzle 39 and again circulated until mixed and vaporized. Thoroughly mixed and vaporized mixture or gaseous fuel discharged into the vortex chamber 45 from the 60 mixing tube 40 passes to the intake manifold through the passage 41 and thence to the motor. The heating chamber 44 surrounds the vortex chamber 45 and the mixing tube 40.

While I have shown in Figure 1 the homogenizing chamber 4 as consisting of a top wall in the shape of two semi-circular arches which turn inside out the entering column of gaseous fuel and assists in imparting to it a 70 whirling motion or vortex before it enters the inlet 2, the said semi-circular arches may be dispensed with and in its place the ordinary manifold may be used. The whirling motion will in that case be formed solely by 75 the injector action of the jet forming inlet nozzle and the mixing tube which is provided with perforations at the lower end thereof.

While I have shown my device in connection with the homogenizing of a gaseous fuel 80 for internal combustion engines, it will be understood that I do in no wise limit my invention thereto. The same may be employed with gaseous fuel burners or may be used wherever it is desired to homogenize vapors, 85 gases and liquids.

The homogenizing action is effected not only by the whirling motion imparted to the gaseous fuel, thereby giving the fuel mixture 90 passing through the manifold an opportunity to gradually vaporize the same but also by the heated walls of the homogenizing chamber 4 which vaporizes the heavier particles or globules of fuel thrown thereagainst.

The mixing tubes 22 and 40 may be omitted and the vortex formed in the vortex chambers by the jet of fuel mixture discharged into the vortex chambers from the jet forming nozzles 25 and 39 though better results 100 are obtained with them.

Various changes may be made without departing from the spirit of my invention as claimed.

I claim:

1. A homogenizer consisting of means forming a vortex chamber, the upper part of the chamber being an annular arch forming a central point, the chamber having a vertical intake passage, a mixing tube within the 110 vortex chamber and discharging against said point, and a plurality of outlets, one of which discharges into the mixing tube.

2. A homogenizer consisting of means of forming an annular vortex chamber, the 115 upper part of the chamber being an annular arch forming a central point, the chamber having a vertical intake discharging towards the said point and an outlet from the vortex chamber, a vertical mixing tube within the 120 chamber, and a peripheral passage connecting the vortex chamber and the mixing tube.

3. A commingling device for carbureted fuels, comprising a casing forming a single chamber provided with a single intake opening in the bottom thereof, and an open-end tube mounted in said casing and in longitudinal alignment with said intake opening, said tube being provided at its lower end with an opening communicating with 130

- said chamber, said casing being also provided with an outlet opening adapted to be connected to the fuel intake passages of an internal combustion engine.
- 5 4. A commingling device for carbureted fuels, comprising a casing forming a fuel commingling chamber, said casing being provided with a fuel intake opening in the bottom thereof, and an open-end tube mounted in said casing and in longitudinal alignment with said fuel intake opening, said tube being provided at its lower end with a plurality of openings, said casing being also provided with outlet openings adjacent to the top thereof, adapted to be connected to the fuel intake passages of an internal combustion engine.
- 10 5. A commingling device for carbureted fuels, comprising a casing forming a chamber provided with a single intake opening 20 in the bottom thereof, and an open-end tube mounted in said casing in spaced relation to the side walls thereof and in longitudinal alignment with said intake opening, said tube being provided at its lower end with 25 an opening communicating with said chamber, said casing being also provided with an outlet opening adapted to be connected to the fuel intake passages of an internal combustion engine. 30

In testimony whereof I have signed my name to this specification.

ERNEST M. WHITE.
